(57) **CLAIM**

The ornamental design for a magnetic core for transformer
for electronic device, as shown and described.

DESCRIPTION

FIG. 1 is a perspective view of the top, front and right side
of a magnetic core for transformer for electronic device
showing our new design;

FIG. 2 is a top plan view thereof;

FIG. 3 is a front view thereof;

FIG. 4 is a left side view thereof;

FIG. 5 is a right side view thereof;

FIG. 6 is a rear view thereof; and,

FIG. 7 is a bottom view thereof.
